[57] CLAIM

The ornamental design for a sectional sofa, as shown and described.

DESCRIPTION

FIG. 1 is a perspective view of a first embodiment of a sectional sofa showing my new design;

FIG. 2 is a front elevational view thereof;

FIG. 3 is a side view thereof, the opposite side being a mirror image of the side shown;

FIG. 4 is a top plan view thereof; and,

FIG. 5 is a rear elevational view thereof.
